UNITED STATES PATENT OFFICE.

PETER ECKMAN, OF GREELEY, COLORADO.

SICKLE-BLADE HOLDER.

1,212,615.

Specification of Letters Patent. Patented Jan. 16, 1917.

Application filed October 9, 1916. Serial No. 124,700.

To all whom it may concern:

Be it known that I, PETER ECKMAN, a citizen of the United States, residing at Greeley, in the county of Weld, State of Colorado, have invented a new and useful Sickle-Blade Holder; and I do hereby declare the following to be a full, clear, and exact description of the invention, such as will enable others skilled in the art to which it appertains to make and use the same.

This invention relates to an improved holder for sickle blades and the like, and an object of the invention is the provision of a device of this kind for holding blades while sharpening the same on a grind stone.

Another object of the invention is to provide a holder of this kind having means, whereby the grinding or sharpening of such blades may be greatly facilitated. For instance, to provide means, whereby the blade may be held at different angles or positions, and at the same time relieve the operator of the weight of the blade, and also prevent the blade from being thrown from the grasp of the operator.

Another object of the invention is to provide a holder having means whereby the blade may be moved to different positions transversely of the grinding stone.

In practical fields the details of construction may necessitate alterations falling within the scope of what is claimed.

The invention comprises further features and combination of parts as hereinafter set forth, shown in the drawings and claimed.

In the drawings:—Figure 1 is a view in perspective of the improved holder constructed in accordance with the invention. Fig. 2 is a sectional view on line 2—2 of Fig. 1. Fig. 3 is a sectional view on line 3—3 of Fig. 1.

Referring more especially to the drawings 1 designates a standard, which may be driven into the ground as shown in Fig. 1, or in any suitable place, and 2 denotes a bracket (which is secured at 3 to some suitable stationary support 4) having a bearing 5 to receive and hold the upper part of said standard. Secured upon the standard by a set bolt 6 is a collar 7. A double bearing member 8 is provided consisting of two sleeves 9 and 10 connected together integrally, one extending at right angles to the other. The sleeve 9 is mounted upon the standard 1 to be supported by the collar 7, whereby the double bearing member 8

may rock, the collar 7 preventing the member from moving downwardly. However, the collar may be adjusted on the standard 1 to hold the member 8 in different positions vertically upon the standard. The sleeve or bearing 10 receives a horizontal rod 11, which is held in said sleeve or bearing 10 by a set bolt 12.

Secured by a set bolt 13 upon one end of the rod 11 is a sleeve 14 which is constructed integral with the disk plate 15, and projecting downwardly from the plate 15 centrally thereof is a pin 16, which passes centrally through a second disk plate 17, and is provided with a reduced end portion 18 to receive the washer 19 and the threaded nut 20, to hold the plate 17 upon the pin 16. Projecting in opposite directions from diametrically opposite points of the disk 17 are two arms 21, and constructed integrally with the outer portions of the arms are downwardly extending spaced forks 22, between which and on the pins 23 anti-frictional rollers 24 are mounted. Engaging between the roller 24 is a transverse bar 25, the outer ends of which are provided with downwardly extending forks 26. Mounted between the forks 26 upon pins 27 are grooved pulleys 28, over which the cable 29 extends. A channel bar 30 is secured in the T-shaped loops or straps 31, by means of the set screws 32. By means of the set screw 32 the bar 30 may be held in different adjusted positions in said looped straps 31. The opposite ends of the cable 29 are secured at 33 to the set screws 32, thereby supporting the blade holding bar 30. The sickle or other blade 34 is arranged in the channel 35 of the holding bar 30. By tightening upon the set screw 32, the opposite flanges 36 of the blade holding bar are forced against the opposite sides of the blades, thereby holding the blade in adjusted positions in the channel of the holding bar. It is to be seen that the blade may be held in different positions by the operator, owing to the arm or rod 11 being allowed to oscillate. Moreover by loosening the nut 20, the arms 21 may be held at different angles relative to the rod 11. Furthermore, the bar 25 may be moved transversely upon the rollers 24, whereby the teeth of the blade may be sharpened, that is one at a time from one end of the blade to the other. Furthermore, the blade may be tilted downwardly or upwardly on one end, farther than the opposite end.

The invention having been set forth what is claimed as new and useful is:—

1. In a holder as set forth, the combination of a vertical support and a laterally extending rod swivelly mounted upon the support to oscillate horizontally, of a transversely disposed member carried by the outer end of said rod and having anti-frictional guides, a transverse bar mounted movable in said guides and carrying pulleys at its outer end, a cable passing over said pulleys, and a blade carrying channel bar connected to the opposite ends of said cable.
2. In a support of the kind set forth, the combination of a vertical standard and a laterally extending rod swivelly mounted upon said standard to oscillate horizontally, means to support the lateral rod in different positions upon said standard, of a member

adjustably carried by the outer end portion 20 of the rod, said member consisting of two disks and means for axially connecting one disk to the other, whereby one may be held adjustably with relation to the other, one of said disks having oppositely extending arms 25 provided with anti-frictional guides at their outer ends, a transverse bar movable in said guides, pulleys carried by the outer ends of said bar, a cable passing over said pulleys and a blade receiving and holding bar connected to the opposite ends of said cable.

In testimony whereof I have signed my name to this specification in the presence of two subscribing witnesses.

PETER ECKMAN.
